UNITED STATES PATENT OFFICE.

HUGH L. ALLAN AND JAMES MOORE, OF BURMAH, BRITISH INDIA, ASSIGNORS TO THE BURMAH OIL COMPANY LIMITED, OF GLASGOW, SCOTLAND, A BRITISH CORPORATION.

APPARATUS FOR SWEATING OR CRYSTALLIZING PARAFFIN OR OTHER WAX.

Application filed October 6, 1923. Serial No. 666,996.

To all whom it may concern:

Be it known that we, HUGH LOGIE ALLAN and JAMES MOORE, British subjects, and both residents of Burmah, British India, have 5 invented certain new and useful Improvements in Apparatus for Sweating or Crystallizing Paraffin or Other Wax, of which the following is a specification.

This invention relates to the manufacture 10 of waxes more particularly paraffin wax, and has for its object to provide an improved stove or apparatus for crystallizing and (or) sweating the paraffin or other wax.

Heretofore it has been usual to depend 15 upon an air circulating system for cooling the scale (wax and oil mixture or waxes of different melting points), particularly when the wax is cooled in trays by air or by the combination of air on the surface and water 20 coils at the bottom of the trays.

In the present invention the wax is kept 25 out of direct contact with air and the tray is covered to form a wax chamber or compartment, and provision is made for effecting uniform heating or cooling of the wax 30 throughout the compartment for which purpose the top and bottom of the compartment may be in contact with water or other cooling or heating liquid.

By this system, complete temperature 35 control can be obtained and, at the same time, more rapid conduction of heat for the same temperature difference between oil and a water-cooled surface than can be obtained between oil and an air-cooled surface. The 40 crystallization can be controlled and the formation of undesirable types of crystals avoided.

In like manner, during sweating, the cake 45 of solidified wax crystals, or crystals and oil, is under complete temperature control and thus even sweating is ensured.

In existing apparatus in which surface 50 cooling of the oil or wax is effected by exposure to air, the surface is more rapidly cooled than the mass, thus tending to the formation of foliaceous crystals which occlude oil, instead of producing acicular crystals from which the oil or lower melting-point waxes drain freely.

Furthermore, in existing apparatus in which the wax is supported on horizontal gauze, it is found necessary to have water

below the gauze in each tray or section, to support the liquefied charge until cooled to 55 the solid phase and the water is drained off before sweating.

According to the present invention, the stove or apparatus preferably comprises a plurality of superposed spaced substantially 60 horizontal plate cells through which a cooling or heating medium may be circulated as desired. The cells are enclosed in an outer shell or vessel of metal or other suitable material which may be jacketed or 65 covered externally with suitable lagging or insulation. Passing through the cells is a charging pipe which may be connected to a pump or other charging apparatus. The spaces between the cells form wax and oil 70 chambers, each having a raised gauze floor. The charging pipe opens into each wax chamber below the gauze and a vent orifice leads from the top of each wax chamber to an air vent or pipe at the top of the outer 75 shell or vessel for the escape of air during charging and for controlled air admission during cooling and sweating.

Preferably a steam pipe passes through the charging pipe to enable the latter to be 80 cleared of solidified wax before sweating. The charging pipe may also have a drain pipe for carrying off sweatings and the finished product.

In the apparatus herein described, the 85 use of water in the wax and oil chamber below the gauze is dispensed with, thus eliminating the necessity for periodically cleaning out the sludge left in the usual trays by the water. A clear space below the 90 gauze is obtained in our apparatus by passing steam or hot water, for a short time through the water cells, after the mass has been cooled, thus melting the wax contained below the gauze and allowing it to run off 95 through the drain pipe.

The invention is hereafter described with reference to the accompanying drawings which illustrate one construction of our improved wax stove by way of example.

Fig. 1 is a vertical section through the stove, with parts broken away and showing gauze around the lowermost heating element.

Fig. 2 is a horizontal section, partly broken away through one of the cells and 105 Fig. 3 is a vertical section at right angles

to Fig. 1. Fig. 4 shows details of one of the heating elements and Fig. 5 is a detail view showing the wax cake (partially sweated) between two heating elements.

5 In the constructional example illustrated, an outer cylindrical shell 10 surrounds an inner shell 11 so as to form a water jacket 12. The inner shell 11 encloses a plurality of cells 13, through which water or steam 10 can be circulated as may be desired. Each cell is preferably slightly inclined as seen in Fig. 1. An oil supply pipe 14 supplies the oil from a pump or other charging apparatus to a cell-charging and sweats-outlet 15 pipe 15 through a valve 16. The spaces 15 between the cells 13 form wax compartments 17 each having a wax-supporting gauze 18 resting on iron rods 19 or other supports. The pipe 15 opens not only into 20 the lowermost compartment 17, but also into an inter-cell charging and sweats-outlet pipe 15^a which in turn opens into the next cell 17 and also into a similar inter-cell 25 charging and sweats-outlet pipe 15^b, and so on throughout the series of cells. Each compartment 17 also has an air pipe 20 which is open to the compartment at the highest point thereof, for the escape of air displaced during charging and for air admission 30 during sweating. Through the series of pipes 15, 15^a, 15^b, 15^c, passes a steam pipe 21 and similarly a steam pipe 22 passes through the air pipe 20 for the purpose of clearing the pipes of wax before sweating. 35 The pipe 15 also has a branch 23 to run off the sweatings and finished product. The uppermost air pipe 20 has an oil overflow pipe 24, a steam or scavenging fluid inlet pipe 25 and an air inlet and outlet pipe 26, 40 the latter controlled by a double-action valve or check-valve 27 actuated by pressure or suction. The lowermost air pipe 20 opens into an oil drain 28.

The compartments 17 are each as shown, 45 provided with a plurality of heating elements 29 (Fig. 4) hung from the cells 13 and open at each end at 30 and 31 to the interior of the cell. Water is circulated through the cells by way of inlet pipes 32 50 and it will be readily seen, on reference to Fig. 2, that the water circulates in a circuitous or sinuous path through the cells 13, its course being interrupted by baffles, partitions or bars 33 which separate the cells 55 into chambers, adjacent chambers being interconnected by the heating elements 29. The water leaves the cells by pipes 34 and may be led into the water jacket 12 by pipes 35, leaving the water jacket by the outlet 36. 60 The water pipes 35 may be fitted with thermometer cups 37 and regulating valves 38. A sludge or drain cock 39 may be fitted to the water jacket 12.

The mode of operation of the apparatus 65 is as follows:—Water or other liquid at a

temperature slightly above the melting point of the scale or wax mixture to be treated is circulated through the cells 13. The wax mixture is then pumped or fed by gravity through the charging pipe 14 and pipe 15 70 into the lower wax chamber 17 in which it rises, the displaced air escaping through the air vent 40 of the air pipe 20 into the upper chamber 17. The lower chamber 17 fills completely, as the air vent 40 is at the highest 75 possible point therein. When the lower chamber 17 is full, the charge continues to rise successively through pipes 15^a, 15^b etc. and fills the upper chambers 17 in succession 80 in the same manner.

The oil is now drained from the air pipes 20 through the pipe 28, air being allowed to enter the chambers 17 by way of the air inlet pipe 26, thus ensuring that a vacuum is not created in the apparatus. Hot air 85 is preferably admitted through the pipe 26, to prevent chilling of the surface of the oil or wax in the compartments 17.

The circulating water entering the pipes 32 is then gradually reduced in temperature, 90 the rate of cooling being suited to the nature of the charge. When the charge is cooled to the desired temperature, a period of rest may be given to establish the crystals.

The valve on branch 23 is then opened, 95 steam is passed through the steam pipe 21 in order to clear the pipes 15^a, 15^b, etc., of solidified scale and sweating is then begun by gradually raising the temperature of the water circulating through the cells 13. Sweating is continued as long as desired and the sweated wax is finally melted out by raising the temperature of the cells 13 by admitting hot water or steam through the pipes 32 or by admitting steam openly or freely to the wax chambers 17 through the steam pipe 25.

In order to promote efficient drainage of the wax during sweating, the centre of the wax cake between each vertical element 29 110 is preferably supported by a gauze partition 41 set vertically along the centre of each space between the vertical elements (see Fig. 5) and the heating elements 29 are surrounded by gauze 42 which extends about half way up the sides of the heating elements and inner shell. As will be seen, by reference to Fig. 5, this arrangement ensures that the wax surface forms a shed 115 from which the sweat readily drain. The wax cake is also supported thereby against sagging.

By the improved apparatus, gradual cooling can be effected during formation of the crystals and the formation of undesirable types of crystals thus avoided. All risk of sudden chilling of any part of the charge is eliminated and fully sweated and purified wax can be produced in a greater quantity 125 in one operation from a given charge of 130

scale or mixture of waxes and/or wax oil of a given melting point and colour than in any known apparatus. Dust or other foreign matter is excluded and as the wax 5 chambers are substantially horizontal, we avoid the disadvantages common to known apparatus of the concentric vertical tube type, in which the wax is supported in the 10 annular space between the tubes and in which sagging of the mass during sweating is common, thus occluding oil or other impurity.

The improved apparatus also permits a thicker cake of mixture to be sweated than 15 can be efficiently sweated in the usual tray type of stove or sweating plant.

The improved apparatus is particularly adapted for the manufacture of paraffin waxes from crude paraffin scale or the like, 20 a feature of the apparatus being its ease of control and the minimum amount of labour required to operate it. The apparatus also does not require to be housed in a specially-constructed building, such as a specially- 25 heated building.

Claims:

1. Apparatus for crystallizing and dry-sweating wax comprising a closed wax-containing chamber, substantially horizontal; 30 hollow heating and cooling cells above and below said chamber, a filling pipe entering said chamber from below and an air-vent at the top of said chamber for the escape of displaced air, whereby said chamber may be 35 completely filled with wax mixture to the exclusion of air.

2. Apparatus for crystallizing and dry-sweating wax as claimed in claim 1 having heating and cooling elements distributed 40 throughout the interior of the wax-containing chamber and a connection from said elements to the hollow cells.

3. Apparatus for crystallizing or sweating wax comprising a plurality of superposed, spaced substantially horizontally heating or cooling cells, a casing enclosing the spaces between said cells to provide enclosed intermediate wax compartments, air vents for said compartments, wax-charging and 45 sweats-discharging means for said compartments, a raised perforated wax support in each compartment and vertical perforated partitions extending upwardly from said support.

55 4. Apparatus for crystallizing or sweating wax comprising a plurality of superposed, spaced substantially horizontal heating or cooling cells, a casing enclosing the spaces between said cells to provide enclosed intermediate wax compartments, air vents for said compartments, wax-charging and 60 sweats-discharging means for said compartments, heat-exchange elements extending into the wax compartment from the cells and 65 open to the interior of said cells.

5. Apparatus for crystallizing or sweating wax comprising a plurality of superposed, spaced substantially horizontal heating or cooling cells, a casing enclosing the spaces between said cells to provide enclosed intermediate wax compartments, air vents for said compartments, wax-charging and 70 sweats-discharging means for said compartments, heat-exchange elements extending into the wax compartments from the cells and 75 open to the interior of said cells and perforated wax supports surrounding said elements.

6. Apparatus for crystallizing or sweating wax comprising a plurality of superposed, spaced substantially horizontal heating or cooling cells, a casing enclosing the spaces between said cells to provide enclosed intermediate wax compartments, air vents for said compartments, wax-charging and 80 sweats-discharging means for said compartments, heat-exchange elements extending into the wax compartments from the cells and 85 open to the interior of said cells and perforated partitions between said elements for 90 supporting the center of the wax cake between adjacent elements.

7. Apparatus for crystallizing or sweating wax comprising a plurality of superposed, spaced substantially horizontal heating or cooling cells, a casing enclosing the spaces between said cells to provide enclosed intermediate wax compartments, air vents for said compartments, a series of coaxial superposed charging and discharging pipes, 95 each opening upwardly into one of the compartments, and an inlet and outlet connection to the lowermost of said pipes.

8. Apparatus for crystallizing or sweating wax comprising a plurality of superposed, spaced substantially horizontal heating or cooling cells, a casing enclosing the spaces between said cells to provide enclosed intermediate wax compartments, a wax-charging and 100 sweats-discharging device for said compartments, a series of air pipes, each opening into the upper part of one compartment and into the adjacent air pipe, an outlet drain for the lowermost pipe, and a valve 105 controlled air inlet or outlet pipe connecting with the uppermost pipe.

9. Apparatus for crystallizing or sweating wax comprising a plurality of superposed, spaced substantially horizontal heating or cooling cells, a casing enclosing the spaces between said cells to provide enclosed intermediate wax compartments, air vents for said compartments, wax-charging and 110 sweats-discharging means for said compartments, heat-exchange elements extending into the wax compartments from the cells and 115 open to the interior of said cells and partitions separating said cells into separate chambers interconnected by said elements.

10. Apparatus for crystallizing or sweat- 120

ing wax comprising a plurality of super-
posed and spaced heating or cooling cells
slightly inclined to the horizontal, a casing
enclosing the spaces between said cells to
5 provide enclosed intermediate inclined wax
compartments, an air vent substantially at
the highest point of each compartment and

a combined charging inlet and discharging
outlet substantially at the lowest point of
each compartment.
